FIRE-RESISTING CABINET

John H. Page, Muskegon, Mich., assignor to The
Shaw-Walker Company, Muskegon, Mich., a
corporation of Michigan

Application July 3, 1944, Serial No. 543,402

unexpanded
vermiculite

4 Claims. (Cl. 109—84)

This invention relates to improvements in fire-resistant files, cabinets, safes or like containers, particularly adapted for the preservation and protection of securities, records, correspondence or other files, against damage or loss from fire.

Fire-resistant containers of the character mentioned usually are provided with a hollow metal casing lined with a suitable heat insulating material. A common form of insulating material is made of gypsum or similar plaster-like material, molded in one piece within the outer casing to form an inner liner therefor.

It has been observed that when the structures of the kind described above are called upon to perform their ultimate function of resisting fire and heat, certain gases are formed within the outer casing particularly when the plaster liner gives up its water of crystallization in the form of steam under excessive heat. Although dehydrolyzation of the lining material is usually relied upon as one of the factors contributing to the protection of the contents of the container, yet the resulting steam pressure generated in the casing tends to separate the outer metal shell from its liner so as to form a hollow space therebetween.

In carrying out my invention I provide an improved form of wall structure for containers of the character described wherein the suitable amount of expandable insulating material, such as vermiculite, is utilized as part of the lining material within the metal casing. Vermiculite has the special characteristic of being expandable under abnormal heat so that when the casing is subjected to fire, the vermiculite becomes expanded and fills the hollow spaces otherwise formed within the metal casing of the container.

The invention may best be understood by reference to the accompanying drawing in which:

Figure 1 is a sectional view of a fire-resistant container as it is manufactured and used.

Figure 2 is a view similar to Figure 1, but showing the container after it has been exposed to destructive fire.

Figure 3 is an enlarged fragmentary section taken through one of the walls of the container shown in Figure 1.

Figure 4 is a section similar to Figure 3, but showing the liner in expanded condition after withstanding fire.

Figures 5, 6 and 7 illustrate different methods which may be employed to apply the expandable lining material to the walls of the container during manufacture.

Referring now to details of the embodiment of

my invention illustrated in the drawing, the invention is shown as applied to a typical form of fire-resistant container suitable for use as a file, cabinet, safe, or the like, indicated generally at 10. The side, top and bottom walls 11, 12 and 13 respectively, each consist of an outer metal shell 14 having an inner liner 15, of high heat-resisting material such as gypsum plaster or other insulating material commonly used in containers of this character. An inner metal shell 16 may also be employed to form an enclosure for the liner, as shown in Figure 3. The liner 15 may be formed as usual in a single piece (excepting for the door) by molding it within the outer shell 14 or by forming a separate hollow mold, and later inserting it within the outer shell. The insulating liner may also be formed of a plurality of separate slabs, or of other insulating material in more or less finely divided state.

The principal feature of my invention consists in disposing a relatively small amount of a heat expandable fire-resisting material within and adjacent the outer metal shell 14, in such position as to increase the effective thickness of the insulating liner, and to fill the voids which otherwise would be formed within the metal shell, when the container is subjected to a destructive fire. I find that vermiculite is especially suitable for this purpose.

Vermiculite is a micaceous mineral, usually consisting of a hydroscopic alteration of mica, which is mined in the form of flaked granules, and is commonly used as an insulating material after it has been subjected to expansion by heat. It derives its name from its peculiar property of expanding under excessive heat in such a manner that the expanded flakes resemble worms. This action is explained by the fact that heat causes the many microscopically thin layers of each grain to expand into greatly enlarged cellular granules in the direction perpendicular to the layers. Ordinarily a batch of vermiculite will expand to about fifteen times its natural volume when subjected to heat of about 350° F. or over. It is used commercially in its expanded state for many kinds of insulation and as an aggregate for plaster and cement where special lightness is desired.

In my invention vermiculite is applied in its natural unexpanded state within the outer metal shell 14 of the container 10, and preferably between said shell and the liner 15, as shown in Figure 3. Various methods of application of the vermiculite may be employed. Figure 5 illus-

trates one method wherein vermiculite in its natural granular state is mixed with any suitable light binding material which will not appreciably interfere with the expansion of the vermiculite, and is applied with a trowel or the like to form a thin layer 19 of, say, one-quarter inch in thickness to the inner surface of the outer shell 14. The main liner 15 is then applied within the outer shell next to said layer of vermiculite in any suitable manner. For instance, if the lining material is molded within the outer shell it can be poured into direct contact with the layer of vermiculite so as to become bonded thereto during the molding process.

Where the lining material 15 is applied to the casing in the form of individual slabs, or in a more finely divided state, it may be disposed in close contact with the inner surface of the vermiculite layer, as indicated in Figure 3.

An alternative method of applying the vermiculite as an adhesive layer to the entire inner surface of the outer shell 14 is shown in Figure 6 wherein the vermiculite is mixed in finely divided granules with a binder, and sprayed directly upon the inner face of the outer shell.

Another method of applying the vermiculite, illustrated in Figure 7, is particularly applicable when the main insulating liner 15 is applied to the structure in the form of individual slabs, which are normally spaced slightly from the outer shell 14 so as to leave room for a thin layer of vermiculite therebetween. In such case the vermiculite may be poured from a hopper 18 directly into the space between the metal shell 14 and the lining material 15. The vermiculite may either be poored in its natural dry state, or again combined with a suitable adhesive binder to hold it in place if desired. Instead of applying the layer of vermiculite to the interior surface of the outer wall or pouring it between the outer wall and the liner as previously described, the vermiculite may also, if desired, be applied to the exterior surface of the insulating lining 15 before the latter is inserted within the casing.

It will now be understood the vermiculite is applied between the outer shell 14 and the lining material 15 in position to become expanded under fire conditions and thus increase the effective thickness of the insulation as the outer walls bulge outwardly due to the pressure of gases generated between the outer shell 14 and the liner 15. It will be further understood that vermiculite can also be applied to the inner metal shell 16 if desired, but it will not be so efficient, and may not even be necessary, if sufficient protection against heat conduction is afforded by the liner 15 and the

layer 19 of vermiculite on the outer face of the latter.

It will also be understood that limited amounts of unexpanded vermiculite can also be employed to special advantage along the joints separating individual slabs of lining material, so as to insure tightly packed joints between adjoining slabs due to the expansion of the vermiculite under fire conditions.

10 Although I have shown and described certain embodiments of my invention, I do not wish to be understood as limiting myself to the specific form and arrangement of materials herein described and shown, but that various modifications thereof may be employed without departing from the spirit and scope of my invention as defined in the appended claims.

What is claimed is:

1. In a fire-resisting container, an outer metal casing having an associated molded hydrous lining of heat-resisting material, and a quantity of vermiculite in its natural unexpanded state disposed in a relatively thin layer between said casing and its lining so as to increase the effective thickness of the insulation within said casing when said vermiculite becomes expanded under abnormal heat.

2. In a fire-resisting container, an outer metal casing having an associated molded hydrous lining of heat-resisting material, and a relatively thin layer of vermiculite in its natural unexpanded state fixed in a binder applied to the exterior surface of said lining so as to increase the effective thickness of the insulation within said casing when said vermiculite becomes expanded under abnormal heat.

3. In a fire-resisting container, an outer metal casing having an associated molded hydrous lining of heat-resisting material and a relatively thin layer of vermiculite in its natural unexpanded state fixed in a binder applied adhesively to the inner surface of said casing in position to expand within the voids produced between said casing and its lining when said container is subjected to abnormal heat.

4. In a fire-resisting container, an outer metal casing having an associated molded hydrous lining of heat-resisting material and a quantity of vermiculite in its natural unexpanded state fixed in a binder to form a relatively thin layer disposed between said casing and its lining in position to expand within the voids produced between said casing and its lining when said container is subjected to abnormal heat.

JOHN H. PAGE.
